UNITED STATES PATENT OFFICE.

HENRY W. JOHNSON, OF MCPHERSON, KANSAS.

SHOCKER.

SPECIFICATION forming part of Letters Patent No. 739,084, dated September 15, 1903.

Application filed March 5, 1903. Serial No. 146,404. (No model.)

To all whom it may concern:

Be it known that I, HENRY W. JOHNSON, a citizen of the United States, residing at McPherson, in the county of McPherson, State 5 of Kansas, have invented certain new and useful Improvements in Shockers; and I do hereby declare the following to be a full, clear, and exact description of the invention, such as will enable others skilled in the art to which 10 it appertains to make and use the same.

This invention relates to shockers for harvesting-machines; and it has for its object to provide an attachment which may be secured to the main or binder frame in position to receive the bundles from the table and which mechanism or attachment after a predetermined number of bundles have been contributed thereto will be automatically operated to discharge the bundles in upright positions 15 and set them upon the ground in the form of a shock, the parts of the mechanism then returning to their original positions to receive other bundles.

Other objects and advantages of the invention 20 will be understood from the following description and include the provision of structural details to insure proper sequence of the steps of the operation.

In the drawings forming a portion of this 25 specification, and in which like numerals of reference indicate similar parts in the several views, Figure 1 is a perspective view of the machine with the parts thereof in position to receive the bundles. Fig. 2 is a side 30 elevation of the attachment with the parts in position to receive the bundles. Fig. 3 is a section on line 3-3 of Fig. 4 on a smaller scale. Fig. 4 is a plan view of the attachment in its 35 final position of discharging the shock. Fig. 40 5 is an elevation showing the mechanism shown at the left of Fig. 2 and with the latch-finger in engaging position. Fig. 6 is a rear elevation of a part of the machine, showing the means for disengaging the latch.

Referring now to the drawings, the presentshocker, which is designed for attachment 45 to the main frame of a harvester and binder, comprises a frame including the longitudinal sills 10 and 11, arranged in parallel relation 50 and connected at their forward ends by the cross-piece 12, the sill 10 having brackets 13 for attachment to the main frame 15 of the

harvester and binder, while the sill 11 is provided with a supporting-wheel 14. It will be noted that the rear end of the frame of the attachment is open. At the forward end of the frame of the attachment is mounted an oscillatory transverse shaft 16, having rearwardly-directed fingers 17, which lie between the sills 10 and 11, and the rear or free ends 55 of which fingers are designed to rise and fall as the shaft 16 oscillates. When the extremities of the fingers 17 move downwardly to their limit, the fingers slant, so that the bundles which are discharged onto the fingers 60 from the table of the main frame may be readily moved from the fingers and at the same time swung into erect positions.

To move a number of bundles simultaneously from the fingers 17 and deposit them in 70 the form of a shock upon the ground, the following mechanism is provided: A head 18 in the form of a plate is provided, the ends of the head being slotted, as shown at 19 and 20, to receive the stems 21 and 22 of the 75 bundle-holding arms of the mechanism, these arms being shown at 23 and 24 and including cross-pieces 25 and 26 at the ends of the stems, and from which cross-pieces extend the 80 pairs of curved members, as illustrated, the arms being so positioned with relation to the head that when the plate is in horizontal position the curved members of each arm will lie one above the other and when the head is in vertical position the curved members of 85 one arm will lie vertically above the curved members of the other arm. As illustrated, the stems of the bundle-holding arms are pivotally mounted in the end slots of the head, so that the opposite ends of the arms may be 90 moved toward and away from each other to grip or release the bundles. Normally the head is in vertical position with the arm 23 below the arm 24 and in close relation to the extremity of the fingers 17, so that the bundles deposited upon the fingers from the 95 binder-frame will lie with their heads upon the arm 23, and if the arms be then caused to grip the bundles and the head be rotated to carry the arm 24 forwardly of the machine 100 and the arm 23 rearwardly the bundles will be gradually moved into erect position and off from the rear ends of the fingers. The bundles may be then lowered to the ground

and the arms operated to release them and then raised above the tops of the bundles and moved to their former positions as the machine progresses.

5 To hold the arm 23 against downward pivotal movement when in position to receive the bundles, the stem 21 is provided with a finger 25', which projects beyond the outer face of the head 18, and in the path of movement in one direction of this finger is a latch or stop 26', which is pivoted to the rear face of the head 18 and is held normally and yieldably in active position by means of the helical spring 28, which encircles the rod 29, attached to the pivoted latch, and rests with its ends against the latch and the eye 30, through which the rod is slidably passed. When the latch or stop is raised against the action of this helical spring, it passes from the path of 20 the finger 25', so that the arm 23 may swing in a direction away from the arm 24 to release the shock, as hereinafter described. The arm 23 is held normally and yieldably against movement in a direction away from 25 the arm 24 by means of the helical spring 31, which is disposed between the inner end of the slot containing the stem and the adjacent face of the stem, the spring being attached at both ends and having such strength 30 that it will return the arm 23 to its normal position when the shock has been released.

To hold the arm 24 spaced to the maximum degree from the arm 23 when the latter is in horizontal position, the stem 22 of the arm 35 24 has a rearwardly-directed lug 32, which projects into the path of movement of the cam 33 on the rod 34, which is pivoted to one end of the head 18 and through the medium of which said head is oscillated on the shaft 40 35, which is slidably mounted in the diagonal slot 36 in the outer side of the frame of the attachment. The rod 34 is connected to the crank-arm 37 on the oscillatory shaft 38, mounted at the forward end of the frame of 45 the attachment and which is oscillated at suitable intervals from the binder mechanism. As the rod 34 moves or swings the head 18 into vertical position the cam 33 is carried into engagement with the lug at the end of 50 the stem of the arm 24, and as this lug is carried around the under face of the cam it is depressed and the arm 24 is raised at its free end or moved away from the arm 23.

To hold the shaft 35 at the upper end of 55 the diagonal slot 36, a cam 39 in the form of a quadrant is formed on the outer or rear face 18 and works against the roller 40 on the pin 41, which projects from the inner face of the outer side of the frame of the attachment, 60 the cam being so positioned that its curved face rests upon this roller when the head is in vertical position and continues to rest upon the roller until the head has reached a horizontal position, when the cam passes beyond the roller and the head, with its arms, may then drop. Connected to the outer end or head of the shaft 35 is a spring 42, connected

also to the post 43 at a point above the shaft, the strength of this spring being sufficient to hold the head, with its shaft, normally in 70 raised position and to permit the head to move downwardly only when the arms thereof bear the weight of a shock. When the shock is released, the spring referred to raises the head so that by operation of the 75 rod 34 the head may be rotated to run the cam 39 onto the roller 41, it being understood that in the rotation of the head the cam holds the head against downward movement, due to the weight of the shock, until after the 80 shock is moved to erect position.

As above described, the separate bundles are successively deposited upon the fingers 17 and the arm 23, the arm 24 being held at the upper limit of its movement, while the 85 arm 23 is prevented from pivotal movement away from the arm 24. As the arm 24 is swung forwardly and downwardly and the arm 23 rearwardly and upwardly by rotary movement of the head 18 the cam 33 passes from engagement with the lug of the stem 22, so that the arm 24 is released and its 90 spring is permitted to draw it tightly against the bundles and hold them between it and the arm 23 in the form of a shock. This 95 rotary movement of the head with the arm is continued until both arms and the head are in horizontal position, at which time the cam 39 has passed beyond its supporting-roller, and the weight of the shock causes 100 the arms and the head to move downwardly to deposit the shock with the bottoms of the bundles upon the ground. As the head 18 travels downwardly it travels also rearwardly by reason of the diagonal or slanting 105 direction of the slot 36, so that the latch 26' is carried downwardly and rearwardly and strikes upon the pin 44 at the side of the frame of the attachment, so that as the head continues downwardly the latch 26' will be swung 110 free from the lug or finger 25' to permit of the arm 23 swinging rearwardly or in a direction away from the arm 24. This rearward-swinging movement of the arm 23 acts to release the shock, and as the machine progresses the arm swings farther to the rear and is then drawn along the side of the shock, and when the machine has passed beyond the 115 shock the spring connected with the stem 21 returns the arm to its original position. As 120 soon as the arms deposit the shock, so that the head is relieved of the weight of the shock, the spring 42 raises the head, and therewith the arms, so that the latch 26' is raised out of 125 engagement with its stop-pin, and the latch is permitted to return to its normal or active position. At this time the lug or finger 25' projects beneath the latch 26', so that the latch does not snap down into its active position until after the spring of the arm 23 has 130 returned said arm to its normal or receiving position. After the head, with the arms, has been raised by the spring 42 the rod 34 returns the head to vertical position, with the

arms in position to receive the next lot of bundles, it being understood that when the head is thus rotated in its raised position the latch 26' is spaced such a distance from its 5 stop-pin on the frame of the attachment that it swings clear of the stop-pin. This is because the axis of rotation of the head has been raised, in which position it is held during the return movement or downward movement of the arm 23 by the cam 39 and the roller upon which it rests.

To tilt the fingers 17 with their free ends downwardly as the head is rotated to deposit the shock, so that the shock may more readily 15 pass from the fingers, the rock-shaft 16 is provided with a crank-arm 45, to which is connected a strap 46, attached to the lower end of the crank-arm of the shaft 38, so that when the upper end of the last-named crank-arm 20 moves forwardly to rotate the head to horizontal position the strap is released and the free ends of the fingers are permitted to drop. When the shaft 38 is rocked in the opposite 25 direction to return the head to vertical position, the strap is drawn upon, so that the shaft 16 is rocked to raise the free ends of the fingers 17.

With this construction it will be seen that by properly timing the oscillation of the shaft 38 the arms may be held in proper position to receive a number of bundles and will then be moved to erect the bundles, then to deposit them, then to release the bundles in the form of a shock, and finally to return to their 35 original positions.

In practice modifications of the specific construction shown may be made and any suitable materials and proportions may be used for the various parts without departing from 40 the spirit of the invention.

What is claimed is—

1. A shocker comprising a head mounted for rotary movement and vertical sliding movement, bundle-clamping arms carried by the head, means for holding the arms in spaced relation to receive bundles, means for actuating the arms to clamp the bundles, means for rotating the head to erect the bundles and means for releasing an arm from its 45 clamping position to deposit bundles.

2. In a shocker, the combination with a frame having a diagonal slot therein, of a shaft slidably mounted in the slot, a head rotatably mounted upon the shaft, a bundle-clamping arm pivoted at each end of the head for movement therewith to lie one above the other or side by side, said arms having lugs projecting at the opposite side of the head and having means for holding them yieldably 55 against separation, a pitman connected to the head and having a cam disposed to engage the lug of the adjacent arm to move said arm in a direction away from the opposite arm as the head is rotated in one direction, 60 a latch in the path of movement of the lug of the opposite arm in the movement of the latter in a direction away from the last-named

arm, means for holding the shaft with the head at the upper end of the slot, and means in the path of the latch when the shaft is at 70 the lower end of the slot, for releasing the latch to permit of pivotal movement of the corresponding arm.

3. A shocker comprising a frame having a downwardly and rearwardly ranging slot 75 therein, a shaft slidably mounted in the slot, a head mounted upon the shaft for oscillation and bodily movement therewith, a cam upon the head, a support for engagement by the cam to hold the head in raised position during a portion of the rotation of the latter, means for holding the head yieldably in raised position, a clamping-arm pivoted at each end of the head and having a lug projecting rearwardly of the latter, a pitman connected with 80 one end of the head and having a cam disposed to engage the lug of the adjacent arm to alternately move said arm away from the opposite arm and release it as the head is oscillated, means for holding said arm yieldably against the action of the cam, a latch in the path of movement of the lug of the opposite arm in the direction of movement of said arm away from the other arm, and means in the path of movement of the latch when the head 85 is rotated in its lowered position, to disengage the latch.

4. A shocker comprising a frame having a downwardly and rearwardly ranging slot 90 therein, a shaft slidably mounted in the slot, a head mounted upon the shaft for oscillation and bodily movement therewith, a cam upon the head, a support for engagement by the cam to hold the head in raised position during a portion of the rotation of the latter, 95 means for holding the head yieldably in raised position, a clamping-arm pivoted at each end of the head and having a stop-lug, a pitman connected with one end of the head and having a cam disposed to engage the lug of the 100 adjacent arm to alternately move said arm away from the opposite arm and release it as the head is oscillated, means for holding said arm yieldably against the action of the cam, a latch upon the head disposed to engage the 105 lug of the opposite arm and hold said arm against movement away from the other arm, means for holding the said opposite arm yieldably against movement away from said other arm, means in the path of movement 110 of the latch with the head in the lowered position of the latter to disengage the latch, pivoted supporting-fingers mounted in the frame, an oscillatory shaft and connections between the oscillatory shaft and the fingers 115 and the pitman for oscillating the head and correspondingly moving the fingers pivotally.

In testimony whereof I affix my signature in presence of two witnesses.

HENRY W. JOHNSON.
